UNITED STATES PATENT OFFICE.

ALOIS F. STEIERT AND OSCAR W. LINKE, OF PHILADELPHIA, PENNSYLVANIA.

FLOOR POLISHER.

Application filed June 2, 1925. Serial No. 34,317.

This invention relates to floor or other surface polishing or treating devices, and the principal object of the invention is to provide a floor-polishing device having certain novel and improved details of construction making for simplicity, strength and comparative cheapness of manufacture.

The invention further resides in the provision of certain novel and advantageous surface-treating and dusting elements constituting detachable and replaceable parts of the device.

Certain embodiments of our invention we have illustrated in the attached drawings, in which:

Figure 1 is a view in perspective of the major part of the casing or container constituting the body of the polishing device;

Fig. 2 is a view in perspective of another part of the casing;

Fig. 3 is a longitudinal section through the assembled casing illustrating the relative positions and cooperative relation between the casing parts shown in Figs. 1 and 2;

Fig. 4 is a section on the line 4—4, Fig. 3;

Fig. 5 is a view in perspective of one of the applicator or floor-treating elements;

Fig. 6 is a view in perspective of the felt or other cover for the casing;

Fig. 7 is a view in perspective of another of the floor-treating elements in the form of a brush;

Fig. 8 is a longitudinal section showing the assembled device;

Fig. 9 is a view in perspective of the device illustrating a modification within the scope of the invention, and

Fig. 10 is a view in perspective illustrating a modified form of retaining means for a floor-treating element.

With reference to the drawings, and particularly to Figs. 1 to 3, inclusive, the device includes a casing which may be advantageously formed of two elements 1 and 2, shown respectively in Figs. 1 and 2, struck up from sheet metal, the part 1 being of substantially rectangular box form open at one side and having its opposite side formed as clearly shown in Fig. 3, to provide a normally convexed flexible section 3. The member 2 consisting of a substantially flat plate having a central depression 4 and at each end an offset 5, and also at the side edges depending flanges 6, is adapted to fit within

55 the member 1 as shown in Fig. 3 to form a

casing closed with the exception of a filling aperture 7 at the bottom of the depression 4. The member 2 may be secured in the member 1 by soldering or any other suitable means.

When secured within the member 1 as shown in Fig. 3, the offset portions 5 of the member 2 each form what in effect are two separate pockets, one pocket lying inside the cover 2 and adapted for reception of weight members 8, the other chamber 9 lying externally of the cover member 2 and adapted for reception of applicator or floor-treating elements, as hereinafter described. It will be noted that the inset flexible portion 3 of the casing member 1 provides shoulders 10, 10, at the ends of the casing behind which the weights 8 are set and which function to retain the weights in their pockets at the ends of the casing. In addition to the parts previously mentioned, the casing, composed of the parts 1 and 2, comprises a pair of trunnion members 11 which may take the form of separate elements lodged in apertures in the sides of the casing member 1, being secured 70 therein in such manner as to provide a watertight joint. These trunnions project beyond the outer side faces of the casing and provide means for attaching a handle, as herein-after more fully described. The side flanges 75 6 of the member 2, when the latter member is assembled with the member 1, extend over the edges and project down the outer side faces of the member 1.

The member 2 also embodies a discharge 90 port 12, and valve mechanism is provided as shown in Fig. 8 for normally closing this discharge port. The valve mechanism in the present instance is supported upon an arm 13 which is secured to the inner side 95 of the part 2, one end of said arm underlying the filler opening 7, and being apertured in registry with the filler opening, the sides of this aperture being threaded for reception of a threaded filler plug 14 which 100 may be threaded into the opening from the outside of the casing, the opening being sealed by means of a rubber or other suitable gasket 15.

The operating parts of the valve comprise 105 an arm 16 pivotally secured at 17 to an arm 18 projecting at right angles from the arm 13, the arm 16 having at one end a relatively soft conical valve element 19 which effectively closes the discharge port 12, as shown 110

in Fig. 8, the other end of the arm 16 normally lying against the flexible and normally extended side 3 of the casing, also as shown in Fig. 8. A spring 20 is also provided which engages the end of the arm 16 and the outer end of the arm 18, and exerts a force tending to retain the arm 16 in such a manner that the valve element 19 normally closes the port 12.

It has been found that an effective seal at the discharge port can be obtained by forming the conical valve element 19 of lead or similar soft metal, and thereafter pressing it firmly into the port 12 that it may conform to the shape of the latter. With the mechanism described, it will be apparent that pressure upon the outside of the flexible portion 3 of the casing will result in an inward flexing of the latter and simultaneously oscillate the arm 16 so as to open the discharge port 12.

Our device further and preferably comprises a pair of floor-treating elements, one of which is shown in perspective in Fig. 5, so formed as to be capable of insertion in the pockets 9 of the casing previously described. These elements comprise in the present instance a substantially rectangular block 21 of such size as to fit the pockets 9 of the casing with a fair amount of snugness, and one side of this block 21 is preferably convexed so that when a felt, or other strip 22, is suitably secured on its outer surface, the outer face of such felt is given a convexed form, as clearly illustrated. These felt strips may be secured to the blocks by means for example of adhesive or by sewing to a strip which extends around the back of each of the blocks, as illustrated in the present instance, in Fig. 8.

The device further comprises a substantially open-sided box-like pad or hood 23 best shown in Fig. 6, which is adapted to receive the casing and to extend over five sides thereof, including the flexible side 3. As clearly illustrated, the pad 23 is provided with apertures 24 for passage therethrough of the trunnions 11 previously described. In practice, it is preferable to use in conjunction with the applicator elements 21-22 and the hood 23, a polishing cloth 25 which preferably extends over and around the hood 23 longitudinally of the casing and also over the tops of the applicator pads 22, the ends of this polishing cloth or fabric strip being confined within the pockets 9 by the said applicators, as clearly illustrated in Fig. 8. This cloth may be replaced when soiled, and not only provides for a clean and soft polishing surface, but helps to retain the hood 23 in position.

In conjunction with the aforescribed elements, we preferably provide with our device a floor-treating element of the type shown in Fig. 7 in the form of a brush or

other element. This element comprises in the present instance a flat rectangular base 26 which forms the backing for the bristles of the brush and is of substantially the same length and width as the casing. At the ends of this base 26, we may provide two fabric strips or flaps 27 which as shown in Fig. 8 may be carried up and over the applicator pads with the ends thereof confined underneath the latter within the pockets 9 whereby the brush element is firmly held in position on one side of the casing.

In addition to the brush or similar element, we may provide a dust pad 28, see Fig. 9, which may be provided with flaps similar to the flaps 27 of the aforescribed brush element, or may have the binding tapes or strips 29, see Fig. 9, which may pass up over the applicator pads and be fastened together by means of a snap or other suitable catch 30 whereby the dust pad is held on the casing.

As an alternative method of applying the floor-treating devices, we may form the latter as shown in Fig. 10, with elements 33 at the back adapted to fit and be frictionally retained in the pockets 9 after the manner of the applicator elements 21-22. In this case, when the brush or other device is to be put into use, the elements 21-22 are removed from the pockets 9 and are replaced by the elements 33 which retain the treating device in position on the casing.

In addition to the parts previously described, we provide a handle 31 whose lower end is bifurcated and is flexible so as to permit its being passed over the trunnions 11 on the casing, as clearly shown in Fig. 9, the handle by reason of the flexibility of the bifurcated ends 32 being easily detachable from the casing if it is desired to remove the pad or hood 23.

The operation of the device will be readily understood by those familiar with the art. With the brush element removed and in a position such that the applicator pads 21-22 rest upon the floor or other surface to be treated, a slight pressure upon the flexible top part 3 of the casing will result in an expulsion of the liquid polishing medium in the interior of the casing onto the said surface. The casing is then reciprocated over the surface by means of the handle 31 to distribute the wax, and when the distributing operation is completed, a reversal of the casing to the position shown in Fig. 8 permit the use of the reverse padded side of the casing for polishing purposes.

As a final polishing operation, the brush 26 may be attached as previously described, and the device then passed over the floor to afford the desired lustrous finish.

As a later operation of maintaining the floors in a clean and dustless condition, the

dust pad 28 may be applied to the device as previously described and the casing passed over the floor in the usual manner.

We claim:

5 1. A polishing device comprising a closed container consisting of two parts, one in the form of an open-topped box and the other in the form of a substantially flat plate having offset end portions adapted to be secured in and having side flange elements extending over the edge of the said box member.

10 2. A polishing device comprising a closed container having weight-receiving pockets at the ends forming an extension of the container chamber, and shoulders on the inner wall of said container defining one side of said pocket and functioning to maintain the weights in position.

15 3. A polishing device comprising an enclosed container having end extensions constituting weight-receiving pockets, one side of said container being formed with an inset normally convexed flexible portion whose ends define one side of said weight-receiving pockets.

20 4. A floor waxing device having a closed box container formed with separate weight and applicator receiving pockets at the end thereof, the latter having an open bottom.

25 5. A floor waxing device having a closed box container formed with separate weight and applicator receiving pockets at the end thereof, said weight-receiving pocket only forming an extension of the container chamber, and said applicator-receiving pocket having an open bottom.

30 6. A container casing for a floor-waxing device comprising an inverted sheet-metal rectangular box; a partial bottom closure for said box having end walls spaced apart from the end walls of the box and provided with horizontal partition-extensions which are joined to the end walls of the box so as to form superposed end pockets; the upper ones of said pockets forming weight-receiving extensions of the liquid container chamber and the lower ones forming open-bottom applicator-receiving recesses.

35 7. A polishing device comprising a casing adapted to hold a polishing medium and

having discharge means for said medium, surface-treating elements detachably secured to one side of said casing, and a surface-treating element secured on the other side of said casing solely by means of said detachable elements.

40 8. A polishing device comprising a container adapted to hold a polishing medium, and discharge means for said medium, surface-treating elements projecting from one side of said container, a surface-treating element adapted to be secured on another face of said container, said element having flexible strips adapted to be confined under the first of said elements whereby the said second element is held on the container.

45 9. A polishing device comprising a container for a liquid polishing medium, and discharge means for said medium, applicator elements projecting from one side of said container, and a surface-treating element having flexible flaps at the ends thereof adapted to be confined under the applicator elements whereby the said surface-treating element is secured to the container.

50 10. A polishing device comprising a container for a liquid polishing medium, and discharge means for said medium, applicator elements projecting from one side of the container, and a surface-treating element adapted to occupy a position on the other side of said container and having flexible retaining elements adapted to pass over said applicator elements and to be secured on that side of the casing.

55 11. A polishing device comprising a container for a liquid polishing medium, and discharge means therefor, applicator elements projecting from one side of the casing, a brush adapted to occupy a position on the other side of the casing, and means including the said applicator elements for securing the brush to the container.

60 12. A polishing device comprising a container having pockets in one side, and a surface-treating member having at the back two projecting elements adapted to be frictionally retained in said pockets.
